UNITED STATES PATENT OFFICE

WILLIAM E. LAWSON, OF WESTFIELD, NEW JERSEY

RAZOR BLADE CONTAINER

Application filed March 19, 1932. Serial No. 600,014.

This invention relates to a container for safety razor blades and has for its primary object to provide a neat and attractive compartmental receptacle for dispensing new blades and for receiving old blades.

A further object of the invention consists in the provision of such a container or receptacle which may be readily supported on the wall of a bathroom or the like, in an out-of-the-way or inconspicuous position.

Another object of the invention resides in the provision of an absorbent liner for the used-blade compartment which may be readily removed and discarded as a unit with the blades therein.

A still further object of the invention consists in the provision of a container having a removable back plate to permit the removal of the used blades.

Other objects and advantages of the invention will be apparent from the following description when taken in connection with the accompanying drawing, in which,

Figure 1 is a perspective view of the container.

Figure 2 is a vertical sectional view through the container.

Figure 3 is a horizontal sectional view.

Figure 4 is a perspective view of the liner for the used-blade compartment.

Figure 5 is a rear elevational view of the container, and

Figure 6 is a view of a modified form of back plate.

Referring to the drawing in more detail the numeral 1 indicates the container proper, which is provided with top, bottom and side walls, 2, 3 and 4, respectively, a front wall 5 and an open rear or back 6.

The front wall 5 has four beveled faces of triangular design, which join in providing an apex 7. The lower one of the beveled faces is provided with a transverse slot 8 through which new blades may be extracted from the container and a slot 9 communicating with

the slot 8 provides an observation opening through which it is possible to determine the approximate number of new blades in the container. The bottom of the container is provided with a slot 10 extending from front

to rear thereof, and providing an opening through which the operator may insert his finger to engage the undersurface and rear edge of the lowest blade in the pack so as to project the same through the slot 8.

The container is divided into an upper compartment for used blades as well as a lower compartment, by means of a horizontal partition 11. The upper compartment for used blades is preferably provided with a liner formed of absorbent material, such as blotting paper or the like, so as to absorb any moisture remaining on blades deposited in the compartment. Such a liner is shown in Figure 4 and is indicated by the numeral 12. This liner is in the form of a folded blank box, which is completely closed and snugly fits within the upper compartment of the container.

Used blades may be deposited in the upper compartment of the container through a slot 13 and it is to be noted that the liner 12 is provided with a similar slit 14 adapted to register with a slot 13 in the container. As will be observed, the slit 14 provides contacting edges which will wipe both sides of the blades as they are inserted into the container. A slot 15 is also provided in a side wall 4 of the container so as to permit the insertion of a charge of new blades into the new blade compartment.

As heretofore mentioned the back of the container is entirely open, as indicated by numeral 6 (Figs. 2 and 3). This opening is normally closed by a plate 16, which has its upper end inserted into and extends upwardly through vertical slots 18 formed at the rear of the side walls 4. The upper wall of a slot 19 formed in the top 2 limits the upper movement of this plate. A vacuum cup or the like 20 is secured to the plate 16 by a rivet 21 or other preferred fastening means, and serves as a support for securing the device on a wall of a bathroom or at any other convenient location.

In Figure 6 is shown a back plate 22 provided with keyhole slots 23, which may be used in lieu of the vacuum cup for supporting the device on a wall or the like.

In the operation of the device it is se-

cured to the wall or other support as indicated in Figs. 2 and 3. When a blade is desired the operator merely inserts his finger in the slot 10 and forces the lowermost 5 blade out through the slot 8. New blades may be inserted in the lower compartment from time to time by inserting the same through the slot 15 and used blades may be stored in the upper compartment by inserting 10 the same through the slots 13 and 14 of the side wall and liner, respectively. When the used-blade compartment is filled, or if it is desired to empty the same for any other reason, the container may be removed from its 15 support by merely raising the same and thus separating it from the back plate 16. When so removed the used-blade compartment becomes accessible and it is merely necessary to withdraw the folded blank box or liner 12 20 and deposit the same in a waste basket or the like; after which a new liner may be inserted and the container replaced upon the back wall 16.

In the foregoing description taken in connection with the accompanying drawing it 25 will be apparent that I have devised a very simple and inexpensive construction of razor blade container; that it is neat and attractive in appearance; that it may be readily supported upon a wall or other convenient base; that it provides storage for both old and new 30 blades; that the new blades may be dispensed singly from time to time as desired; that means is provided for removing the moisture 35 from deposited used blades; and that the used blades may be discarded by simply withdrawing the liner from the container and 40 depositing it in a waste receptacle.

In accordance with the patent statutes I 45 have described what I now believe is the preferred form of construction, but inasmuch as various minor changes may be made in certain of the details without departing from the spirit of the invention, it is intended that all such changes be included 50 within the scope of the appended claims.

What I claim is:

1. In a device of the class described, a container for used razor blades, said container 55 provided with a slot for the entrance of the blades, a preformed liner substantially fitting within the container, said liner provided with a slit registering with the slot in the container, whereby each blade is wiped as it is deposited in the container.

2. In a device of the class described, a container for used razor blades, said container provided with a slot for the entrance of the blades, a preformed liner of absorbent material 60 substantially fitting within the container, said liner provided with a slit registering with the slot in the container, whereby each blade is wiped as it is deposited in the container.

3. In a device of the class described, a con-

tainer provided with an entrance slot for razor blades in one side thereof, a removable rear side, and a set-up liner fitting the interior of the container and provided with a slit 70 registering with the slot of the container, whereby each blade is wiped as it is inserted in the container.

4. In a device of the class described, a container provided with an entrance slot for razor blades in one side thereof, a removable rear side, a vacuum cup fixed to the exterior of the rear side for supporting the same on a wall or the like, and a set-up liner fitting the interior of the container and provided with a slit having contacting walls and registering with the slot of the container. 75
